CLAIM

The ornamental design for a toothed scraper bar for earthmover bucket, shown and described.

DESCRIPTION

FIG. 1 is an isometric view of design for a toothed scraper bar for earthmover bucket showing our new design;

FIG. 2 is a rear elevational view thereof;

FIG. 3 is a top view thereof;

FIG. 4 is a front elevational view thereof;

FIG. 5 is a bottom view thereof;

FIG. 6 is a right end elevational view thereof;

FIG. 7 is a left end elevational view thereof; and,

FIG. 8 is a reduced isometric view showing the design in use, the broken line showing of the earthmover is for illustrative purposes only, and forms no part of the claimed design.
